GEORGE W. BAUGHMAN, OF PITTSBURGH, PENNSYLVANIA, ASSIGNOR TO THE UNION SWITCH & SIGNAL COMPANY, OF SWISSVALE, PENNSYLVANIA, A CORPORATION OF PENNSYLVANIA

METHOD AND MEANS FOR SUPPLYING CURRENT TO TRACK SECTIONS

Application filed September 10, 1931. Serial No. 562,094.

The present invention relates generally to train-control systems, and has more particularly reference to trackway means whereby a broken rail in a track-section may be detected on the train and the latter controlled accordingly.

In train-control systems of the character in which a train-control current in the rails of a track section is utilized to influence a signal and/or brake valve on the train, it sometimes occurs that the train-carried equipment will be effectively influenced even though one of the rails of the track-section is broken. This is especially true where the rails form the return conductor for a propulsion current for the train, because in systems of this character impedance bonds span the insulation that separates one track section from another, and the train-control current will therefore at times sneak across from one rail to another. This is clearly a disadvantage because while traffic conditions of adjacent blocks or track sections may be such as to permit unrestricted or but slightly restricted speed of a train through a given track section, yet the presence of a broken rail may constitute a dangerous condition that should be indicated on the train so that the speed of the train may be lessened.

The main object and feature of this invention is to devise a system whereby only a train-control current of a character to indicate restricted speed can be impressed on a track section having a broken rail notwithstanding the existence of non-restrictive traffic conditions in one or more adjacent track sections and notwithstanding the fact that the particular track section is itself clear or unoccupied.

In the accompanying drawing, the invention is disclosed in a concrete and preferred form which shows a diagrammatic representation of a track system designed to carry out the above objects and features.

1, 2 and 3 indicate three adjacent track sections, composed of traffic rails, which sections are separated from each other by means of insulated joints 4. 5 indicates the usual impedance bonds spanning the insulation. Each track section is provided with a track relay

T-1, T-2 and T-3 respectively, and with a track transformer the secondary 6 of which is bridged across the rails of a section. It is, however, unnecessary to describe the wiring and other elements in connection with all of the track sections since that would be mere repetition, and the description will therefore be confined mainly to the elements associated with section 2, reference being only made to such elements of the other sections as may be necessary to an understanding of the invention. VR² indicates a coding relay which is held energized as long as track relay T-2 is energized, its circuit being from a suitable current source over front contact 7 of T-2, conductor 8 and conductor 9 back to the same source. The main function of the coding relay, when energized, is to supply to the track uninterrupted alternating current from a suitable source by way of front contact 10, conductor 11, conductor 12, primary 13 of the track transformer and then back to the source. When deenergized it opens the circuit to the track-transformer at 10 and closes a circuit through a coding device 14 by way of back contact 15. At the same time it closes a circuit at back contact 16 from coding contact 80, 120 or 180 to primary 13 by way of conductors 17, 18 and 12. It is unnecessary to describe coding device 14 and all of the circuits that control current from contacts 80, 120 and 180; suffice it to say that contacts 120 and 180 are responsive to traffic conditions of one or more track sections in advance, and that 80, 120 and 180 represent means whereby different codes, or current interrupted or varied a different number of times during a given period, can be impressed on the track section so as to give different indications on a train occupying such section. Of the three codes represented by 80, 120 and 180, the 80 code indication is the most restrictive.

VA indicates a control relay having a circuit from a source of current over back contact 19 of coding relay VR¹, wire 20, front contact 21 of track relay T-2, wire 22 and wire 23 back to source. It will be seen that when relay VA and track relay T-3 are energized and VR² is deenergized a coded cur-

rent can be supplied from a suitable current source over front contact 24 of T-3, wires 25 and 26, front contact 27 of VA, and wire 28, through either 120 or 180 coding contacts, wire 17, back contact 16, wires 18 and 12, to primary 13 and back to source. On the other hand, if VA is deenergized, even though T-3 is energized, the 120 and 180 codes cannot be applied to the rails of the track section 2 because the circuit will then be from source over front contact 24 of T-3, wire 25, back contact 29 of VA and wire 30 to contact 80, wire 17, back contact 16 of VR², wires 18 and 12 to primary 13 and back to source. If track relay T-3 is deenergized then the circuit will be from source to back contact 31, wire 30, contact 80, wire 17, back contact 16 of VR², wires 18 and 12, to primary 13 and back to source. Each track relay is so designed that it will pick up when supplied with coded current.

Let us now assume that a train is in section 1, and that section 2 is unoccupied. In these circumstances track relay T-1 and consequently coding relay VR¹ will become deenergized and will close the circuit through VA at back contact 19. As the train enters section 2, from section 1, track relay T-2 releases and coding relay VR² becomes deenergized by its circuit being broken at 7. As previously described, this disconnects at 10 the steady current source from primary 13, closes at 15 the circuit for the coding device 14 and closes a contact at 16 between wires 17 and 18. The deenergization of track relay T-2 also opens contact 21 thereby rupturing the previously described circuit for control relay VA. However, relay VA has a slower release than relay VR², so that, before VA releases, VR² will have closed back contact 32 so that a circuit is established through VA from a suitable source of current over back contact 32, over wire 33, front contact 34 of VA, wires 35 and 36, front contact 37 of T-3, wires 38 and 22 to VA and then by wire 23 back to source. Should T-3 be in its released position at this time, then the circuit for VA will be as before except that from wire 35 current will flow over back contact 39 and wire 40 to wire 38, since if T-3 is released so will repeater relay 41 be released, and therefore if contact 37 is open, contact 39 will be closed. The result of all this is that relay VA remains energized, and the coded current can flow from either 80, 120 or 180 depending upon traffic conditions of the section or sections in advance. When the train enters section 3 from section 2, and 3 is not already occupied, then track relay T-3 releases and thereby deenergizes repeater relay 41, but 41 is slower in its release than VA so that the circuit through VA will be ruptured before contact 39 is closed. In these circumstances, the previously described circuit from contact 31 (now closed because T-3 is de-

energized) through coding contact 80 to primary 13, will be established so that when the train has left section 2, coded current from 80 will be placed on the rails of section 2, track relay T-2 will pick up, thereby closing a circuit at 7 through coding relay VR² and so rupturing the circuit at 15 through the coding device 14 and closing a circuit at 10 to again place steady current on the rails. The energization of VR² also opens contact 32.

Let us now assume that the train in passing through section 2, broke one of the rails. Under these conditions, track relay T-2 would not pick up when the train has left section 2, relay VR² would remain deenergized and the coding device would continue to run. Consequently, another train entering section 1 would not be able to energize control relay VA, because although T-1 and VR¹ would release and close contact 19, T-2 would not be energized and contact 21 would therefore be open. When said other train therefore enters section 2, it cannot, regardless of traffic conditions in advance, receive a less restrictive indication than that supplied by coding contact 80 because contact 27 would be open and 29 would be closed. Therefore, assuming T-3 to be energized, coded current would flow from the source over contact 24, wires 25 and 26, to contact 29, over wire 30 to 80 and thence by 17, 16, 18 and 12 to primary 13 and so back to source. Again, if T-3 is down, when the other train enters section 2 under the circumstances recited, the coded current will be from a source over contact 31 of T-3, wire 30, coding contact 80, and over 17, 16, 18 and 12 to primary 13 and back to source. Thus with a broken rail in section 2, coded current less restrictive than 80 will not be placed upon the rails of section 2 notwithstanding clear traffic conditions in sections ahead and notwithstanding the fact that section 2 is otherwise clear.

Although I have herein shown and described only one form of apparatus embodying my invention, it is understood that various changes and modifications may be made therein within the scope of the appended claims without departing from the spirit and scope of my invention.

Having thus described my invention, what I claim is:

1. A track circuit system including: a track section, circuit means including a coding device to supply any one of a plurality of coded currents to said track section, means controlled by traffic conditions of another section to determine which of the coded currents is to be impressed on the track section, a track relay for said section which when deenergized starts the coding device in operation, and means to prevent any but a certain coded current from being impressed on the track section if the track relay fails to pick up after being deenergized and before be-

ing shunted by the entry of a train into the track section.

2. A track circuit system including: a track section, circuit means including a coding device to supply any one of a plurality of coded currents to said track section, means controlled by traffic conditions of another section to determine which of the coded currents is to be impressed on the track section, a track relay for said section which when deenergized starts the coding device in operation, and a relay to prevent any but a certain coded current from being impressed on the track section if the track relay fails to

10 pick up after being deenergized and before being shunted by the entry of a train into the track section.

3. A track circuit system including: a track section, circuit means including a coding device to supply any one of a plurality of coded currents to said track section, means controlled by traffic conditions of another section to determine which of the coded currents is to be impressed on the track section, a track relay for said section which when deenergized starts the coding device in operation, and a relay controlling said circuit means and controlled by the track relay of its own section and by the track relay of

25 the section in rear of the first-mentioned track section.

4. A track circuit system including: a track section, circuit means including a coding device to supply any one of a plurality of coded currents to said track section, means controlled by traffic conditions of another section to determine which of the coded currents is to be impressed on the track section, a track relay for said section, a control relay for said circuit means to be energized when the track relay of its own section is energized and the track relay of the section in rear of the first-mentioned track section is deenergized, and a coding relay to be deenergized when the track relay of its own section is deenergized to thereby start the coding device in operation and to maintain the control relay energized.

5. A track circuit system including: a track section, circuit means including a coding device to supply any one of a plurality of coded currents to said track section, means controlled by traffic conditions of another section to determine which of the coded currents is to be impressed on the track section, a track relay for said section, a control relay for said circuit means to be energized when the track relay of its own section is energized and the track relay of the section in rear of the first-mentioned track section is deenergized, a coding relay to be deenergized when the track relay of its own section is deenergized to thereby start the coding device in operation and to maintain the control relay energized, and means controlled

by the track relay of the track section in advance to deenergize the control relay when said track relay of the section in advance becomes deenergized.

Signed at Swissvale, in the county of Allegheny and Commonwealth of Pennsylvania, this 8th day of September, 1931.
